GEAR WHEEL LAPPING TOOL

Theodore R. Rideout, Pittsburgh, Pa., assignor
to Westinghouse Electric & Manufacturing
Company, a corporation of Pennsylvania

Application April 2, 1931. Serial No. 527,179

5 Claims. (Cl. 51—204)

My invention relates, generally, to lapping tools and, more particularly, to lapping tools utilized for lapping the teeth of large gear wheels.

5 In order to construct a gear wheel which will withstand the severe shocks and heavy loads to which it is subjected in service, it is necessary to harden it, after the teeth are cut, by subjecting it to a heat-treating process. This process, 10 invariably, causes the teeth of the gear wheel to become distorted. In order to minimize the errors caused by these distortions, the teeth are lapped by a lapping tool, since the teeth are too hard to be re-surfaced by a cutting tool.

15 In general, the lapping process comprises applying an abrasive compound on the teeth of a gear wheel and then reciprocating it in-and-out of a lapping tool. The lapping tool is disposed to encircle the gear wheel and is provided with 20 inwardly projecting complementary teeth which mesh with the teeth of the gear wheel. In order to provide for lapping all the teeth evenly, the gear wheel is disposed to be turned within the lapping tool by indexing the teeth, one at a time, 25 at the beginning of each reciprocatory movement.

Although the process of lapping gear teeth has been applied to small gear wheels, it has never been applied to large gear wheels, because 30 of the difficulty encountered in constructing large lapping tools. In constructing a lapping tool for small gear wheels, a solid lapping member is cast around the teeth of a dummy gear wheel, which is essentially like the gear wheel 35 to be lapped. However, in order that a substantially long lapping stroke and the proper clearance between the lapping tool and the gear wheel to be lapped, may be provided, the dummy gear wheel is provided with a wider face and a 40 slightly larger diameter than the corresponding dimensions of the gear wheel to be lapped.

In endeavoring to construct a lapping tool for large gear wheels, many attempts were made to cast a solid lapping member around a large 45 dummy gear wheel in the same manner as for small gear wheels, but such attempts were unsuccessful because internal stresses were set-up during the cooling of the metal. The internal 50 stresses were so great that either the solid lapping member broke or the dummy gear wheel was crushed. In order to overcome this difficulty, the dummy gear wheel was heated in order to provide a similar shrinkage to that of the 55 solid lapping member, but this method was also

unsuccessful because of the fusion of the two members.

Also, several attempts were made to cast individual lapping members, which covered only a small section of the teeth of the dummy gear wheel, but these attempts were unsuccessful because the internal stresses would warp the individual lapping members, and, consequently, produce a different radius of curvature than that of the dummy gear wheel.

An object of my invention is to provide for forming individual lapping members for a lapping tool by pouring molten metal adjacent to the teeth of a dummy gear wheel having the same teeth contour as that of the teeth of the gear wheel to be lapped, whereby the individual lapping members are restrained from warping during the cooling process.

Another object of my invention is to provide for forming individual lapping members for a lapping tool by pouring molten metal into the space provided intermediate a dummy gear wheel and an annulus which is disposed to encircle the dummy gear wheel.

A further object of my invention is to provide for mounting individual lapping members on a support whereby adjustments may be made to compensate for the wearing of the lapping members, caused by the lapping process.

Other objects of the invention will hereinafter become apparent.

This invention, accordingly, is disclosed in the accompanying drawing and comprises the features of construction, the combination of elements and the arrangement of parts which will be exemplified in the construction hereinafter set forth and the scope of the application of which will be indicated in the claims.

For a fuller understanding of the nature and the objects of the invention, reference should be had to the following detailed description, taken in connection with the accompanying drawing, in which:

Figure 1 is a plan view illustrating the arrangement of the parts utilized in constructing a lapping tool embodying the features of my invention, comprising a dummy gear wheel centrally disposed within an annulus having cores equally spaced.

Fig. 2 is a plan view with parts in section illustrating the same elements that are shown in Fig. 1, with the addition of a body of metal in the spaces provided between the dummy gear wheel and the annulus, thus forming a plurality of individual lapping members;

Fig. 3 is a plan view of a lapping tool constructed in accordance with my invention, parts being broken away to show the bolts that are utilized to connect the individual lapping members to the annulus;

Fig. 4 is a sectional view of a lapping tool taken along the line IV—IV of Fig. 3, and a gear wheel which is disposed to be lapped.

Fig. 5 is a fragmentary sectional view of my lapping tool, illustrating, particularly, the shims, whereby the lapping members may be adjusted in order to compensate for wear.

Referring now to the drawing, 12 designates, generally, an annulus which is utilized to construct my lapping tool. As shown, it is disposed to encircle a dummy gear wheel 10, preparatory to the pouring of the molten metal for forming the individual lapping members 18. The annulus is constructed to have a face of substantially the same width as the face of the dummy gear wheel. Also, it is of such size as to be strong enough to restrain the lapping members from warping away from the dummy gear wheel.

In order to form a plurality of individual lapping members, a plurality of cores 14 are provided at evenly spaced intervals, between the dummy gear wheel and annulus. Any number of cores may be utilized, the number depending somewhat upon the size of the gear wheel to be lapped.

When molten metal is poured, for forming the lapping member, it completely fills the space intermediate the dummy gear wheel and the annulus, except that space which is stopped off by the cores. Upon the cooling of the molten metal, the annulus restrains the lapping members from warping away from the teeth of the dummy gear as they would have done had the annulus not been utilized.

However, in order to keep the magnitude of the internal stresses which are set-up during the cooling process, from becoming excessive, the width of the space between the dummy gear wheel 10 and the annulus 12 is made as small as possible. It will be observed that, by pouring a plurality of individual lapping members instead of one continuous member between the dummy gear wheel and the annulus, the stresses are smaller, because each member is free to contract linearly.

After cooling, and before the dummy gear is removed, the annulus 12 and the individual lapping members 18 are drilled and tapped in order that they may be secured together by bolts 20. It has been determined that, if the webbed recess 11 of the dummy gear wheel 10 is filled with cool water, and the annulus 12 is heated, the dummy gear wheel may be readily removed.

In order to provide for adjusting the lapping members relative to the annulus whereby means may be provided to compensate for wear, shims 26 are utilized. As shown in Fig. 5, the shims 26 are inserted intermediate the individual lapping members 18 and the annulus 12.

In view of the fact that means of any suitable type may be utilized to reciprocate the gear wheel in-and-out of the lapping tool, only a showing of the essential parts is included in the drawing, such as, for example, in Fig. 4, a gear wheel 24 is disposed on a shaft 25 which may be reciprocated by a suitably operated piston.

At first, since the teeth of the lapping members may be imperfect, the lapping process laps

not only the errors that may be present in the teeth of the gear wheel, but also the errors that may be present in the teeth of the individual lapping members. However, it will be observed that the teeth of the lapping members become more nearly perfect the more the lapping tool is utilized, and eventually, substantially all the lapping will occur on the teeth of the gear wheel instead of on both.

While the illustrated example constitutes a practical embodiment of my invention, I do not limit myself strictly to the exact details here illustrated, since the structure and the method of making it may be considerably varied without departing from the spirit of the invention, as defined in the appended claims.

I claim as my invention:

1. A lapping tool utilized for lapping the teeth of gear wheels comprising, in combination, a plurality of segmental lapping members, an annulus for supporting said lapping members, means for detachably securing the lapping members in spaced relation to the annulus, the lapping members having teeth thereon, the contour of said teeth constituting a lapping surface for so lapping the teeth of gear wheels that the contour and the position of each tooth of the gear wheel, when lapped, relative to each successive tooth thereof, are the same.

2. A lapping tool utilized for lapping the teeth of gear wheels comprising, in combination, an annulus, a sectioned lapping member disposed within said annulus and having teeth formed thereon, the contour of said teeth constituting a lapping surface for so lapping the teeth of gear wheels that the contour and the position of each tooth of the gear wheel, when lapped, relative to each successive tooth thereof, are the same, means for detachably connecting the lapping member to the annulus, and means for adjusting the segmental lapping member relative to the annulus in order to compensate for the wear caused by the lapping process.

3. A lapping tool utilized for lapping the teeth of gear wheels comprising, in combination, a plurality of segmental arcuate lapping members having teeth formed thereon, means for supporting said lapping members, the contour of said teeth constituting a lapping surface for so lapping the teeth of gear wheels that the contour and the position of each tooth of the gear wheel, when lapped, relative to each successive tooth thereof, are the same, means for detachably connecting the lapping members to the said supporting means, and means for adjusting the segmental lapping members relative to the supporting means in order to compensate for the wear caused by the lapping process.

4. The method of constructing a lapping tool utilized for lapping the teeth of gear wheels comprising constructing an annulus having a greater internal diameter than the external diameter of the gear wheel to be lapped, constructing a dummy gear wheel having the same teeth contour as that of the teeth of the gear wheel to be lapped, positioning the dummy gear wheel within the annulus, positioning a plurality of core members between the dummy gear wheel and the annulus, pouring molten metal into the remaining space intermediate the dummy gear wheel and the annulus, thus forming a plurality of segmental arcuate lapping members having lapping surfaces adjacent to the teeth of the dummy gear wheel and removing the dummy gear wheel from the annulus.

5. The method of constructing a lapping tool utilized for lapping the teeth of gear wheels comprising constructing a supporting member having an opening larger than the gear wheel 5 to be lapped, constructing a dummy gear wheel having the same teeth contour as that of the teeth of the gear wheel to be lapped, positioning the dummy gear wheel within the opening of the supporting member, positioning a core member 10 between the dummy gear wheel and the sup-

porting member, pouring molten metal into the remaining space intermediate the dummy gear wheel and the supporting member, thus forming a sectioned lapping surface of the lapping tool adjacent to the teeth of the dummy gear wheel 80 removably securing the segmental lapping member to said supporting member, and removing the dummy gear wheel from the supporting member.
